UNITED STATES PATENT OFFICE

117,388

DESIGN FOR A SURFACE COATING SPREADING TOOL

Teofil Woinarovicz, Worcester, Mass.

Application August 3, 1939, Serial No. 86,436

Term of patent 7 years

To all whom it may concern:

Be it known that I, Teofil Woinarovicz, a citizen of the United States, residing at the city of Worcester, in the county of Worcester and State of Massachusetts, have invented a new, original, and ornamental Design for a Surface Coating Spreading Tool, of which the following is a specification, reference being had to the accompanying drawing, forming part thereof, in which:

Fig. 1 is a perspective view of a spreading tool showing my new design.

Fig. 2 is a front elevational view.

Fig. 3 is an edge view.

I claim:

The ornamental design for a surface coating spreading tool, as shown.

TEOFIL WOINAROVICZ.
